UNITED STATES PATENT OFFICE.

GUSTAVE A. CARLSON, OF DETROIT, MICHIGAN.

POLISHING MACHINE.

Application filed August 19, 1920. Serial No. 404,647.

To all whom it may concern:

Be it known that I, GUSTAVE A. CARLSON, a citizen of the United States of America, residing at Detroit, in the county of Wayne, 5 and State of Michigan, have invented certain new and useful Improvements in Polishing Machines, of which the following is a specification, reference being had therein to the accompanying drawings.

10 This invention relates to polishing or buffing machines, and has for its object to provide a means by which articles of approximately rectangular cross section may be polished or buffed.

15 In the operation of the device, the work is rotated slowly while being held with a uniform pressure in contact with a polishing wheel.

In the drawings:

20 Figure 1 is an end elevation partly in section;

Fig. 2 is a plan view of my machine, showing the position of the work in its relation to the buffing wheel;

25 Fig. 3 is a side elevation; and

Fig. 4 is a detail view, partly in section of the work holding clamp.

A suitable base 1 has longitudinally extending ways 2 in which the slide 3 is 30 adjustably mounted, its adjustment being effected by the screw 4 and hand wheel 5. A sliding carriage 6 is connected with the slide 3 by a toggle 7 having a handle 8. This arrangement permits adjustment of the carriage along the base by means of the screw, while allowing rapid withdrawal of the carriage from its advanced position by the use of the toggle. On the carriage 6, is a support 9, vertically adjustable by means 35 of the screw 10 and hand wheel 11. A swinging frame 12 is pivoted at its lower end to the support 9 and mounted on the upper end of this frame is an electric motor 13, connected by the belt 14 and pulley 15, 40 to drive the worm 16, worm gear 17 and shaft 18.

At the end of the shaft 18, the work holder 19 is secured in any suitable manner, and the size and shape of this work holder will of course be modified to suit varying conditions. As an illustrative example of the sort of work for which this present invention is particularly adapted, I have shown a tapering pan 20 of substantially rectangular cross section. For such a piece of work, the work holder 19

may consist of a block of wood shaped to fit the interior of the pan and secured to the shaft 18 by screws (not shown) passing through holes in the flange 21 at the end of the shaft 18. Projecting forward from the carriage 6, is an arm 22 carrying at its forward end a pulley 23, which forms a guide for the cord 24 attached at its rear end to the swinging frame 12, and at its forward end provided with weights 25. A bracket 26 on the arm 22, supports a rod 27 extending laterally and having at its outer end a similar bracket 28, in which a vertically disposed rod 29 is mounted for vertical adjustment. At the upper end of the rod 29, a wheel 30 is mounted for rotation in contact with a portion of the work holder 19. If desired, this guiding section of the work holder may be provided with a metal band 31 acting as a wear plate. The weight 25 through the cord 24 and pulley 23 holds the swinging frame 12 with uniform pressure in a substantially upright position, and by means 70 of the hand wheel 5, the sliding carriage 6 may be adjusted to bring the work mounted on the work holder 19 into sufficient contact with the buffing wheel 32.

As the shaft 18 is rotated by the motor 13, the work mounted on the work holder 19 is turned so as to present all its sides successively to the buffing wheel, the weight 25 maintaining a uniform pressure and the wheel 30 acting to prevent the work holder 90 from being drawn too far forward by the weight 25.

A suitable clamp may be provided to hold the work 20 on the work holder 19, and as an example, I have shown a clamp head 95 33 adjustably mounted on a bent rod or L-shaped arm 34, one leg of the L being slideable in a supporting bracket 35 carried by a standard 36 on the swinging frame 12. A split sleeve 37 is clamped on the rod 34 100 to serve as an abutment for a spring 38 enclosed in the chamber 39 formed in the end of the bracket 35. A cam sleeve 40 is secured at the rear end of the rod 34 and the pressure of the spring 38 on the abutment 37, holds the cam on the sleeve 40 in engagement with a cam on another sleeve 41. The arrangement of the cam surfaces is such that rotation of the cam sleeve 41 by means of its handle 42 in one direction 110 forces the rod 34 to slide in its bracket 35 against the action of the spring 38, thus

bringing the clamp head 33 into contact with the work at a point in line with its axis of rotation with the work holder on the shaft 18. Rotation of the sleeve 41 in 5 the opposite direction releases the rod which is moved by the spring to withdraw the clamp head 33 from contact with the work. A dowel 43 engaging a socket 44 prevents rotation of the rod 34 in its bracket 35 when 10 the head 33 is in clamping position.

By the use of the means described herein one workman can operate a series of machines, placing the work in position on each in succession and replacing the pieces 15 as the polishing is completed, by unpolished pieces, without having to devote his entire attention to a single piece, as in the ordinary machines in use hitherto. After the sides of the pans are polished in a machine of this 20 type, the bottom and interior are polished by other machines.

I claim:—

1. A machine for presenting work to a 25 polishing device comprising a base, a carriage slidably mounted on the base, a support mounted on the carriage, means for adjusting the support vertically on the carriage, a swinging frame pivoted to the sup-

port, a rotatable work holder carried by the swinging frame, gravity-operated means to 30 move the swinging frame forward, and means for rotating the work holder.

2. A work holder mounted for rotation and having a portion to engage the interior of hollow work, and a clamping member 35 comprising an L-shaped arm mounted to engage the exterior of the work at the axis of rotation, a bracket in which the arm is slidably mounted a clamping head on one portion of the arm, and a cam on the other 40 portion of the arm to force the clamp head into contact with the work.

3. A work holding clamp comprising a bracket, an L-shaped member having one leg 45 of the L mounted for sliding movement in the bracket, a clamp head adjustably mounted on the other leg of the L, and positive means for moving the L-shaped member in the bracket to cause the clamp head to engage the work. 50

In testimony whereof I affix my signature in presence of two witnesses.

GUSTAVE A. CARLSON.
